UNITED STATES PATENT OFFICE.

JULES F. WEGMANN, OF CHICAGO, ILLINOIS.

DESIGN FOR A GAME-BOARD.

SPECIFICATION forming part of Design No. 34,678, dated June 18, 1901.

Application filed March 25, 1901. Serial No. 52,872. Term of patent 14 years.

To all whom it may concern:

Be it known that I, JULES F. WEGMANN, a citizen of the United States, residing at Chicago, in the county of Cook and State of Illinois, have invented and produced a novel 5 Design for a Game-Board; and I do hereby declare the following to be a full, clear, and exact description of the invention.

My invention relates to a novel design for a 10 game-board, the object being to provide a novel device of this character; and it consists in the features of the design hereinafter fully described and claimed.

The accompanying drawing illustrates my 15 design.

The board is provided with a diagram having the general shape of a six-pointed star, but of irregular outline. The entire area bounded by this outline is divided into equal 20 hexagonal spaces. The center field is hexago-

nal in general outline and is separated from the points of the star by means of a heavy line which forms the boundaries between adjacent hexagonal spaces in the center field and the points of the star. Each of the points 25 of the star contains eleven hexagonal spaces, while the center field contains seventy-three of said spaces. The outline of the diagram is also formed of heavier lines than those dividing the center field and the star-points 30 into hexagonal spaces.

I claim as my invention—
The design for a game-board, substantially as shown and described.

In testimony whereof I affix my signature 35 in presence of two witnesses.

JULES F. WEGMANN.
